PC(57) **CLAIM**

The ornamental design for a motor for a railway vehicle, as shown and described.

DESCRIPTIONFIG. 1 is a front, top and right side perspective view of a motor for a railway vehicle showing my new design;
FIG. 2 is a rear, bottom and left side perspective view thereof;

FIG. 3 is a front view thereof;

FIG. 4 is a rear view thereof;

FIG. 5 is a top view thereof;

FIG. 6 is a bottom view thereof;

FIG. 7 is a left side view thereof; and,

FIG. 8 is a right side view thereof.

The parts shown in the broken lines do not form part of the claimed designs. The dot and dashed lines mean a boundary between the claimed portion and the non-claimed portion.
